UNITED STATES PATENT OFFICE.

WILLIAM JOSEPH STILL, OF TORONTO, CANADA.

VARIABLE-SPEED GOVERNOR.

SPECIFICATION forming part of Letters Patent No. 700,848, dated May 27, 1902.

Application filed April 23, 1900. Renewed April 10, 1902. Serial No. 102,262. (No model.)

To all whom it may concern:

Be it known that I, WILLIAM JOSEPH STILL, a subject of the Queen of Great Britain, residing at Toronto, in the county of York, in the Province of Ontario, Canada, have invented certain new and useful Improvements in Variable-Speed Governors, of which the following is a specification.

My invention relates to improvements in variable-speed governors; and the object of my invention is to design a governor of the class described that will be automatic in its operation; and it consists, essentially, of a spring-controlled arm pivoted to a revolving support, suitable means being operated by said pivoted arm for regulating any suitable valve-gear that determines the amount of motive power supplied to the revolving support, means being in the path of movement of said pivoted arm for controlling movement of same, as hereinafter more particularly explained.

Figures 1, 2, 3, 4, and 5 are face views of my governor, parts being removed, showing the position of the parts of the governor at different periods of their operation. Fig. 6 is a vertical section on the line $x-y$, Fig. 5.

In the drawings like letters of reference indicate corresponding parts in each figure.

Journaled in the bracket A^4 and in the standard A^5 is a stub-shaft A^6 . The standard A^5 is supported upon suitable legs B . Keyed to the outer end of the stub-shaft A^6 is a ring a' , the outer periphery of which is eccentric, as shown at a^8 . The stub-shaft A^6 is cut away on its under side, forming a passage-way A^8 , (see Fig. 6,) in which operates the head A^9 of the operating-arm B' , which is pivoted at b to the end of the shaft A . The shaft A is driven by any suitable means, said means being controlled by a valve-gear which regulates the supply of motive power to the said operating means. Above the passage-way A^8 the stub-shaft A^6 is semicircular in cross-section, as shown at A^{10} , and is provided on its upper side with a lug a^2 . Secured to the bearing-bracket A^4 is a spring a^3 , which normally rests in contact with the lug a^2 . The object of this spring is to keep the stub-shaft A^6 in the position required by engaging with either side of the said lug when the stub-shaft is turned. Each end of the semicircularly-formed portion A^{10} is preferably be-

eled, as shown at a^4 and a^5 . Near the lower end of the arm B' is a weight b^2 , suitably secured thereto. The object of this weight is to balance the weight of the arm B' around its pivot b , so that the said arm will not be affected by oscillations or shocks imparted to the mechanism.

Journaled on the eccentric ring a' is an arm B^3 , connected by the pin b^4 to the supporting-arm B^2 , which is secured by the pin b^3 to the lower bearing portion of the standard A^5 .

O^2 is a spring connecting the supporting-arm B^2 with the operating-arm B' .

B^4 is a guard secured at b^5 to the standard A^5 .

O^3 is a lug secured to or forming part of the lower bearing portion of the standard A^5 .

O^5 is an arm stiffly pivoted by the pin O^6 to the arm B^3 . Loosely journaled on the pin O^6 is a swinging plate O^7 , to which is secured near its upper forward end the escapement-plate O^9 .

O^{10} is an escapement-pawl secured at O^{11} to the operating-arm B' .

The swinging plate O^7 is prevented from moving down too far by means of the pin L^2 , secured to the arm O^5 .

L^3 is a spring extending from under the pin L^2 around the pin O^6 and is secured by its end l to the swinging plate O^7 . The object of this spring is to keep the plate O^7 in its normal position.

The arm O^5 is provided with a handle o .

Having now described the parts of my governor, I shall describe its operation. It will be seen on reference to the drawings that immediately after the end O^4 of the arm B' escapes the lug O^3 there are two forces acting upon the said arm—viz., the force created by the rotation of the shaft A driving the arm upwardly and the force of the spring O^2 tending to rotate the said arm around its pivot b . The whole governing effect of the mechanism is produced by the speed with which the arm B' is driven upwardly and by the distance through which the said arm has to be moved by its pin b after the end O^4 escapes the lug O^3 before the escapement-plate O^9 comes within the radial path of the escapement-pawl O^{10} . The frequency with which the governor operates to increase or diminish the supply of motive power to the operating means for the shaft A is changed by altering the distance

that the escapement-plate O^9 extends into the radial path of the escapement-pawl O^{10} . It will be seen from this that there is no necessity to alter the initial tension of the spring O^2 to vary the speed of the shaft A. During the following-described operation the shaft A is supposed to be driven at its maximum speed. The said shaft being revolved in the direction indicated by arrow raises up the operating-arm B' , Fig. 3, and brings the notch a^6 of the head A^9 into contact with the beveled end a^4 and moves the stub-shaft A^6 around in the direction indicated by arrow, thus moving the lever X, Fig. 6, connected thereto (which for illustration controls any suitable valve-gear connected with operating means for the shaft A) and decreases the amount of energy imparted to the said operating means for the said shaft. Simultaneously the above-described operation takes place the eccentric ring a' , keyed to the stub-shaft A^6 , moves the arm B^3 and the escapement-plate O^9 farther into the radial path of the escapement-pawl O^{10} , thereby enabling the required time to elapse before the arm B' will operate the stub-shaft A^6 to increase the speed of the shaft A. When the operating-arm B' descends, its end O^4 abuts the lug O^8 , moving the said arm into the position shown in Fig. 4. When the end O^4 escapes the lug O^8 , the escapement-pawl O^{10} will again be intercepted by the escapement-plate O^9 , as the said escapement-plate is thrown farther into the radial path of the said escapement-pawl and will merely repeat its former motion. This will be continued until the speed of the shaft diminishes in proportion to the distance the escapement-plate O^9 has been inserted into the radial path of the arm B' , when the escapement-plate O^9 will fail to intercept the escapement-pawl O^{10} , and the spring O^2 will bring the head A^9 of the arm B' against the guard B^4 , and the said head will slide upwardly in contact with the said guard, (see Fig. 5,) bringing the notch a^7 into contact with the beveled end a^5 , thus moving the stub-shaft A^6 into the position shown in Figs. 1, 2, and 5, thus through the valve-gear increasing the supply of motive power to the means which operates the shaft A. The position of the arm B' when it is being dominated by the spring O^2 and drawn into the position shown in Fig. 5 is shown dotted in Fig. 4. Simultaneously the operating-arm B' has moved the stub-shaft A^6 and its connected parts into the position shown in Figs. 1, 2, and 5 the eccentric ring a' has moved the arm B^3 to normal, thus diminishing the distance that the escapement-plate O^9 extends into the radial path of the escapement-pawl O^{10} . As a result of the before-described operation the speed of the shaft A increases; but the escapement-plate O^9 being now farther from the radial center of the escapement-pawl O^{10} the arm B' , although engaging with the lug O^8 , as formerly, will for a time continue to be dominated by the spring O^2 and pass by the escapement-plate O^9 and will simply repeat the

motion last described. As the speed of the shaft increases the time given for the spring O^2 to act upon the arm B' will diminish in proportion to the increase in the speed of the shaft A, so that the escapement-pawl O^{10} during an upward movement of the arm B' will again be intercepted by the escapement-plate O^9 , and the first-described operation will be repeated. The reason for the relative movement of the escapement-plate O^9 by the eccentrically-journalized arm B^3 nearer to or away from the radial center of the escapement-pawl O^{10} at each change in the position of the stub-shaft A^6 is to prevent the governor from being too sensitive to slight variations in the speed of the shaft A.

The ends o^2 and o^3 of the escapement-plate O^9 and escapement-pawl O^{10} , respectively, are preferably knife-edges. If at any time during the upward movement of the operating-arm B' the knife-edge o^3 should contact with the knife-edge o^2 of the escapement-plate O^9 , said escapement-plate will, as it is spring-held, give and allow the operating-arm B' to move to the limit of its upward stroke, and thus enable the said parts to operate as if there were no obstruction.

In case I wish the shaft A to be kept driven at its maximum speed I throw the arm O^5 upwardly around the pin O^6 , thereby throwing the escapement-plate O^9 out of the radial path of movement of the escapement-pawl O^{10} . Consequently the spring O^2 brings the head A^9 in contact with the guard B^4 , and the arm B' having to keep this position at each revolution of the shaft A goes through the operation before described of operating the stub-shaft A^6 into position shown in Figs. 1, 2, and 5. In case I wish to stop the shaft A, I throw the arm O^5 downwardly (when the parts are in the position shown in Figs. 3 and 4) around the pin O^6 , thereby throwing the escapement-plate O^9 so far into the radial path of the escapement-pawl O^{10} that the said escapement-pawl will abut said escapement-plate whenever the end O^4 escapes the lug O^8 . The escapement-pawl O^{10} therefore cannot pass by the escapement-plate O^9 and permit the head A^9 of the arm B' to operate the stub-shaft A^6 , so as to cause increased energy to be supplied to the operating means for the shaft A. The supply of energy to the said operating means for the said shaft having been reduced, the said shaft will slow down to its minimum speed, when the energy for the said operating means for the said shaft can be in any suitable manner entirely cut off.

I of course do not confine myself to the construction herein shown and described, as the same may be altered in many ways without departing from the spirit of my invention.

What I do claim as my invention, and desire to secure by Letters Patent, is—

1. A variable-speed governor comprising a crank attached to a revolving support held in suitable bearings, a spring-controlled arm pivoted to said crank, a lug placed in the path

- of movement of said arm so as to operate said spring-controlled arm at each revolution of said revolving support, as described, a guiding-plate placed in the path of movement of said arm so as to guide the movement of said arm above or below said plate as the speed of the support rises or falls, and means in the path of said arm, being operated by same, for regulating the speed of said revolving support, as set forth and for the purpose specified.
2. A variable-speed governor comprising a crank attached to a revolving support held in suitable bearings, a spring-controlled arm pivoted on said crank, a lug placed in the path of movement of said arm so as to operate said spring-controlled arm at each revolution of said revolving support, as described, a guiding-plate placed in the path of movement of said arm so as to guide the movement of said arm above or below said plate as the speed of the revolving support rises or falls, means for varying the position of said guiding-plate relative to the path of movement of said arm for increasing or diminishing the speed of said revolving support, and means in the path of said arm, being operated by same, for regulating the speed of said revolving support, as set forth and for the purpose specified.
3. A variable-speed governor comprising a crank attached to a revolving support held in suitable bearings, a spring-controlled arm pivoted on said crank, a lug placed in the path of movement of said arm so as to operate said
- spring-controlled arm at each revolution of said support, as described, a guiding-plate 35 placed in the path of movement of said arm so as to guide the movement of said arm above or below said plate as the speed of the said support rises or falls, automatic means for varying the position of said guiding-plate relative to the path of movement of said arm for increasing or diminishing the speed of said revolving support, and means in the path of said arm, being operated by same, for regulating the speed of the said revolving support, 45 as set forth and for the purpose specified.
4. A variable-speed governor comprising a crank attached to a revolving support held in suitable bearings, a spring-controlled arm pivoted on said crank, a lug placed in the path of movement of said arm so as to operate said arm at each revolution of said revolving support, and a spring-controlled guiding-plate 50 in the path of movement of said spring-controlled arm incapable of offering fracturing 55 resistance to the motion of said arm in case of contact between said arm and said spring-controlled plate, as set forth and for the purpose specified.

In testimony whereof I have signed my name to this specification in the presence of two subscribing witnesses.

WILLIAM JOSEPH STILL.
